UNITED STATES PATENT OFFICE.

CHARLES H. ANDERSON, OF SAN FRANCISCO, CALIFORNIA.

CARGO-CONVEYER.

SPECIFICATION forming part of Letters Patent No. 761,810, dated June 7, 1904.

Application filed February 19, 1903. Serial No. 144,071. (No model.)

To all whom it may concern:

Be it known that I, CHARLES H. ANDERSON, a citizen of the United States, residing in the city and county of San Francisco, State of California, have invented an Improvement in Cargo-Conveyers; and I hereby declare the following to be a full, clear, and exact description of the same.

My invention relates to an apparatus which is especially designed for conveying cargo or other material from the holds of vessels or like receptacles to places of deposit more or less distant therefrom.

The object of my invention is to unite in a single apparatus all the means necessary to unload any part of a cargo of most any description from any part of a ship, which apparatus shall be adjustable according to the character and amount of cargo and to the rise and fall of tides and in which apparatus the conveying means shall be continuous, coördinate, and automatic in operation. To this end I employ a vertically-adjustable elevator-leg suspended and operated from a point of support independent of the vessel to be unloaded with means for elevating the cargo either in the form of packages, bales, sacks, or in bulk in the form of coal, coke, loose grain, or other material of similar description. Lateral and supplementary feeders are disposed fore and aft and in the wings of the ship, by which the cargo is delivered to the foot of the leg, which is designed to be lowered into the cargo as the latter is removed from the vessel and to raise the cargo and deliver it upon a horizontally-traveling carrier suitably suspended and adjustable with relation to its support, and with relation to which carrier the leg is also adjustable up and down and also adapted to swing to such angle as may be necessary in gathering the cargo within the vessel's hold.

My invention also comprises details of construction which will be more fully explained by reference to the accompanying drawings, in which—

Figure 1 is a general elevation of my apparatus. Fig. 2 is a general plan of same. Fig. 3 is a side elevation of elevator-leg. Fig. 4 is a plan view of parts of same. Fig. 5 is a transverse section of same. Fig. 6 is a de-

tail of floor and controlling device. Fig. 7 is a detail of lower end of floor. Fig. 8 is a diagrammatic view of driving devices. Fig. 9 is a diagrammatic view of side bar or guide device. Fig. 10 is a detail of same. Fig. 11 is a rear view of discharging-block. Fig. 12 is a transverse section of same. Fig. 13 shows saddle mechanism and feed-conveyer connections for bucket elevator. Fig. 14 illustrates the connection of longitudinal and transverse feed-conveyers. Fig. 15 is a front elevation of lower end of bucket elevator. Fig. 16 is the belt-compensating device on horizontal conveyer. Fig. 17 illustrates the connection of horizontal conveyers. Fig. 18 is a plan view of same, showing motor attachment when driven independent of elevator. Fig. 19 illustrates the attachment of the flights to the chains. Fig. 20 is a cross-section of Fig. 16. Fig. 21 illustrates the connection of the conveyer-frame B' to the saddle and shows the belt 50^a and its pulley 50^b. Fig. 22 is an enlarged plan view, broken away, of the left-hand end of Fig. 4. Figs. 23, 24, and 25 are details of the cross-head and connections.

The elevator-leg A consists of a vertically-disposed steel lattice-work frame, which is suspended in a saddle 40, (to be described later,) carried at the outer end of a horizontal carrier frame or boom B, the inner end of which carrier B is in turn supported upon a tower, derrick, mast, or equivalent support, as C, which support is adapted to stand upon a wharf if the vessel is to be discharged upon the same side, or it may be mounted upon a barge, as here shown at D, which is located by the side of the vessel opposite from the point of cargo delivery. The method of supporting the elevator-leg is such that it may be moved up and down with relation to the boom B to suit varying heights of tide, position of vessel, and depth to which the elevator may have been sunk into the cargo, so that whatever position it may occupy it is adapted, first, to receive the cargo from its lateral feeders in the hold, lift the cargo to the plane of the shore conveyer B' and discharge it upon said conveyer, which delivers it at the desired point. The general construction of the elevator-leg A is well illustrated in Figs. 3, 4, 5, 6, 7. It

comprises the endless flight-carrying chains 3, passing over the sprockets 4 at the ends of the frame. Between the planes of said chains is a floor or cargo support of pipes 2 or the like adjustable with relation to the flights 3^a. The latter extend transversely between the chains and serve as supports upon which boxes or packages of any description may be placed and raised, the boxes or burdens resting 10 against the floor 2 and being supported in front by the adjustable guides 5. The attachment of the flights to the chains is shown in Fig. 19 and is such that they may be readily inserted or removed and the spaces between them changed at will. The floor is adjusted with relation to the flights to suit the size of the packages, so that the latter are supported against the floor in their upward movement. The guides 5 are so located with relation to 20 the flights that they prevent the packages or burdens from falling outwardly and retain them in place until they arrive at the point where they are to be discharged upon the horizontal shore carrier B'. These guides are 25 preferably made in telescoping sections, as in Fig. 3, and may be connected at their upper ends with carrier B', as at 5^b, whereby they are regulated relative to the depth of the elevator below said carrier. The means by which 30 the cargo is delivered to the foot of the elevator and the means for operating the elevator, the shore carrier, and the lateral and supplemental feed-carriers within the ship continuously, simultaneously, and from the 35 same source of power will be described hereinafter. The flights may be made in any suitable manner. I have here shown them as made of angle-iron of sufficient strength for any load they are liable to carry and having suitable connections, as at 3^b in Fig. 19, with the ropes or chains upon each side. Angle-iron guides 6 also serve to support the 40 ends of the flights and the ropes or chains 3, to which they are attached and by which they are moved. In order to adjust the floor with 45 relation to the flights, I have shown longitudinal shafts 7, carrying pinions 8, which are adapted to engage with slideable rack-frames 9, Figs. 6 and 7, said rack-frames being at 50 right angles to the line of flights or transverse to the length of the elevator and supporting the floor 2. These shafts are journaled at their ends in sleeves 23, carried by the shafts of sprockets 4, and are turnable by means of 55 transverse shafts 10, Fig. 4, and worm-gears 11, so that if small packages are to be transferred the floor may be correspondingly brought toward the flights, and if large packages are to be raised then the floor can be 60 correspondingly moved away from the flights, thus producing such a relation between the floor and the flights that the burden lying upon the latter will be supported against the floor and, passing under the guides 5, pivoted 65 to links 5^a, will be prevented from falling

outwardly until it reaches its point of delivery. The operation of shaft 10 is effected by a hand-wheel 10^a. For the purpose of correspondingly adjusting the sides of the elevator and conveyer with relation to the packages or burdens, so that the latter are properly supported from each side, I have shown guide-bars 12 upon each side, and these guide-bars are supported at the inner ends of crank-arms 13, fixed upon the upper ends of shafts 14, journaled in frame A. Shafts 14 are turnable by means of worm-wheels 15, Figs. 9 and 10, engaging worms 16 upon horizontal shafts 17, having hand-wheels or equivalent devices 18, by which they may be turned. 70 19 represents wheels around which pass the ropes 20, which connect the shafts on opposite sides of the carrier, so that they are turnable in pairs or series to adjust the guides 12 in unison. By means of turnbuckles or 75 equivalent devices, as at 21, any slack in the ropes may be taken up. It will be seen by this construction that the guide-bars or sides 12 carried by the crank-arms may be caused to approach or swing in over the carrier-belt 80 to any desired degree to receive and guide small packages and may be correspondingly separated for larger packages, thus preventing the packages from getting out of place during their transportation over the carriers. These guide-bars are adapted to both 85 the elevator and the horizontal carrier. The lower ends of the pipes or strips of which the floor 2 is composed are bent around the shaft of the lower sprocket-wheel, as shown 90 at 22, Fig. 7, and the two shafts 7, carrying the pinions which adjust the floor, are connected to the shaft of the sprocket-wheel 95 as follows: These shafts 7 pass through and are slideable in sleeves 23, which in turn have 100 other sleeves 23^a transverse to them embracing the shaft 24 of the lower sprocket-wheel. The sprocket-wheel shaft can thus be moved 105 backward and forward by the take-ups without interfering with the arrangement of the pinion-carrying shafts 7. As it is impossible 110 to place any bracing across the frame to support the end of the floor, it can practically only be supported by means of these attachments, which are plainly shown upon the detail view, Fig. 7. A slight bend or offset is 115 made in the floor, just above the lower end, as shown at 26, which prevents the load from binding or pinching against the floor when, as in the case of sacks thrown upon the flights, 120 they might otherwise become jammed between the flights and the floor. When the burden reaches the point where it is to be delivered upon the horizontal shore carrier B', it contacts with a triangular block, 27, Fig. 12, 125 which is so fixed that it acts to tilt the burden and discharge it from the vertical elevator-leg upon the transverse carrier-belt of B', which belt is adjustable, as shown in Fig. 16 and as 130 will be described later, whereby the space be-

- tween the end of B' and the flights may be varied according to the size of the packages being carried by the flights. This belt has adjustable side bars 12', operated in the same manner as those previously described in connection with the elevator A, thus maintaining the packages in the proper position while being delivered by this shore conveyer. The deflecting-block 27 is moved up and down by a cable, as 28, which is wound upon a drum, as 29, near the top of frame A. This drum is actuated by a friction-clutch, as 30, Fig. 22, operated by a bell-crank lever 31 and a rod 32, extending down along the frame to within reach of an operator who may be stationed upon a platform located alongside of the horizontal conveyer and adjacent to the vertical elevator. The deflector 27, Figs. 11 and 12, may be held at any desired point by a pin or bolt 33, entering holes in a longitudinal metal strip 33^a upon the floor 2. In order to adapt the block relatively to the floor, the flights, and the size of packages conveyed, its deflecting-surface comprises a series of conjoined sections jointed, as at 34, and supported at their upper ends rigidly by brace-rods 35, which are jointed and foldable in the middle. Thus by folding one or both of these brace-rods down upon the main portion the outer portion of the triangular block will be contracted to any desired degree, so as to clear and be out of the way of the flights when small packages are being carried and the floor correspondingly brought nearer to the flights. The lower side of the block has the concaved grooves 36, made to fit the semicircular floor-pipes 2 and to allow the block thus to form projections, which extend between the pipes composing the floor to prevent sacks or soft packages from being caught at this point. When the block is to be lowered relative to the movement of the elevator-leg to suit the position of the cargo, the clutch is released and a brake-shoe 100, operated by a cord or connection 101, Fig. 22, is applied to the drum until it has been let down to the desired point.
- The means for suspending the elevator-leg and adjusting it vertically in relation to the cargo-level is as follows: A saddle 40 is secured to the outer end of boom B, and the saddle and boom are suitably supported, as by the whip 41, from the top of the tower, derrick, or mast C, on which the boom is swiveled and slidable. The elevator-frame passes vertically through the saddle and is guided in its up and down adjustments thereby. The elevator end of the frame of carrier B' may be pivotally supported on the saddle. The whip 41, passing over a pulley or sheave 42 at the top of a mast, goes down to a winding-drum or winch 43, whereby the whole apparatus may be raised and lowered to suit conditions, and when desired the elevator, boom, and shore conveyer may be lifted free from the vessel and folded up against the derrick or

mast C. Chains or cables 44, attached to the saddle, pass down on each side of the elevator-leg and attach to drums or chain-wheels 45, located near the lower end of the leg. By revolving the drums 45 in one direction or the other the chains are wound or unwound to raise or lower the leg. Any suitable means may be employed to operate chain-wheel 45 either by hand or by the same power used to drive the burden-carrier on the elevator. I have shown for the latter purpose a rod 39, running nearly the length of the leg, slidable in suitable guides and adapted to be grasped by the operator at any level of the ship. This rod 39 extends nearly the length of the leg, and it connects with the lever shown by dotted lines in Fig. 3, said lever connecting with a friction-gear 38^a on the shaft of the lower sheave 51, as shown in Fig. 4, said gear 38^a meshing with a friction-pulley on the shaft of the hand-wheel 46, which shaft has the gears 45^a, which by a chain of gears of any well-known and appropriate character (not shown) drives the chain-wheels 45. In case it is not desired to use the main driving power of the machine the drum may be actuated through suitable hand operating mechanism, as at 46.

The burden-carrying chains 3 and the shore conveyers are operated from a source of power located exterior to the ship. Where flights are used—as shown, for instance, in Figs. 1, 3, 4, 5—the driving connections for the elevator and shore carriers are represented in diagrammatic view in Fig. 8, in which the endless driving-belt 50 passes around the sheaves 51 at top and bottom of the elevator-frame. Thence the two parts of the belt approach each other and pass around idler-sheaves 52 52', thence around the respective inner sheaves 53 53', which direct the two parts one up to and over a counterweighted tension-pulley 54 and the other downward around sheave 55, uniting with the other part and receiving motion through belt 56, which passes over a pulley on the shaft of sheave 55 and is driven from any suitable source of power. Motion may be transmitted from belt 50 to drive both the shore and elevator conveyers in unison, the former through connections 50^a with sheave 52, the latter through suitable connections interposed between the shaft of the upper sheave 51 and the shaft of the adjacent sprocket-shaft 4. The belt or connection 50^a connects with a pulley on the shaft of pulley 50^b on the shore conveyer B', as in Figs. 16 and 21. The starting and stopping of the burden-carrier on the elevator may be controlled by a rod 37 and suitable clutch mechanism, as at 35^a in Fig. 22, and which may represent any well-known and appropriate form of clutch mechanism. By these connections it allows the elevator-leg to be raised or lowered and thrown into any position without interfering with the operation of the driving mechanism or the arrangements

by which it is connected with the shore end of the apparatus. In order to allow for movements of the vessel and barge forward or back with relation to each other, the sheaves 52 52' and 53 53' are journaled in swiveled carriers 57, Fig. 8, which are turnable from one side to the other, so that whatever change of position may take place in the elevator and parts connected therewith this construction will 5 allow the pulleys and their shafts to turn, so that they are always truly in plane with each other, while boom B has universal joints at both ends to allow for independent movements of the vessel and barge.

15 In order to compensate or adjust the length of the horizontal belt of carrier B' in relation to the flights, so that it may be brought near to the elevator when the packages are small and prevent their falling between the two or 20 moved farther away to clear the elevator when the packages are larger, in Fig. 16 I have shown a carriage 76, movable in suitable and well-known guides on the frame of B' and having pulleys 58, around which passes the 25 carrier-belt 59. The carriage is adjustable by means of a rack-and-pinion mechanism 77, as shown, to compensate for the lengthening and shortening of the belt, according as the carriage is projected more or less beyond the 30 elevator end of B'.

The inner end of the boom rests upon a cross-head upon the support C, and this is suspended by a suitable hoisting-tackle, so that it may be raised or lowered. In Figs. 35 23 and 24 I show the swivel connection of boom and cross-head 102, whereby the boom has a universal movement and the cross-head may be raised and lowered. The cross-head is connected by ropes 83', attached to eyes 83 40 on the cross-head and leading over pulleys on the mast C to one of the drums 43. The elevator-leg is also steadied by stays extending from the top, as shown at 66, to an appropriate cleat or eyebolt or other well-known fastening at 66' to maintain its proper position when being adjusted with relation to the cargo 45 during the operation of transferring it.

I now come to the means by which material is delivered to the foot of the leg A. Endless conveyers 60 extend laterally fore and aft from the hatchway in which the leg is suspended, and each of these lateral conveyers may have one or more supplemental conveyers, as 61, extending into the wings of the 55 ship. These conveyers, of which there may be as many as required, are driven in unison from and with the elevator, which latter, we have previously seen, operates in unison with the shore conveyer. The driving-gear of 60 these conveyers 60 61 and their connections with chain conveyer 3 are as follows: The lower sprockets 4 are connected, through suitable gearing 62, as indicated in Fig. 15, with the drums on the adjacent ends of carriers 60. 65 A line-shaft 60^a extends parallel with each car-

rier 60 and is journaled on the frame thereof and is operated, through suitable connections, with the drum at the elevator end of said carrier. At suitable intervals these shafts carry gears 60^b. The discharge ends of carriers 61 70 each have a carriage 61^a, Fig. 14, provided with rollers 61^b, which are movable on a track 61^c, of channel-iron, disposed parallel with shaft 60^a. The roller end of the lateral carrier 61 runs on the track, and the shaft 60^a 75 has the gears 60^b at intervals, which protrude through slots in the side of the channel-iron 60^c, whereby the belts of the carrier 61 are driven. A chain of intermeshing gears are journaled in carriage 61^a, and by moving a 80 carrier 61 to a point to engage these gears with a gear 60^b on shaft 60^a motion is transmitted to the carrier. Thus a package put upon a carrier 61 in a remote part of the vessel's hold will be taken and delivered upon 85 carrier 60, thence to the foot of elevator, thence lifted by an attendant, if necessary, and discharged upon shore carrier B', and finally deposited upon the wharf or in the 90 warehouse without further handling than the first deposition of it upon carrier 61.

In order to lift coal, wheat, or other loose material, it is necessary to employ buckets, as at 3^b, which are secured to the endless chains 3, so as to be carried upward in the 95 same manner as the flights 3^a, previously described. When the buckets reach the level of the shore carrier, they are discharged thereon as follows: The chains 3 are caused to change from a vertical to an essentially horizontal 100 travel by direction drums or pulleys 62^a, journaled in saddle 40', Fig. 13. The buckets are thereupon tilted to discharge into a chute 63, which delivers the material upon the shore 105 conveyer, as shown. The chain of empty 110 buckets then passes around the direction pulleys or drums 64 and 65, journaled in the saddle, whence they are brought again into a vertical line above the horizontal conveyer, and the empty buckets are thus carried over the 115 top and returned down to be again loaded. As pulleys 62^a, 64, and 65 are journaled in the saddle, they in nowise interfere with the vertical adjustment of the leg. By suitably-disposed gearing power may be transmitted to 120 revolve the direction drum or pulleys at 64 to provide a direct pull upon the chains at this point and insure an easy movement around the direction-pulleys. In the present instance power is transmitted to drive the bucket-carrying chains through belt 50, which passes from the pulleys as 53 53' of Fig. 1 around the direction-pulleys 78 79 80, Fig. 13. Pulley 79 through suitable gearing (indicated at 125 81) transmits motion to a master-gear 82 on sprocket 64. Thus the leg may be raised and lowered here, as before, without disturbing the driving mechanism. Where the distance from the elevator-leg to the point of deposit is very great, the land or shore conveyer B' may be 130

made in sections and jointed, as shown in Figs. 17 and 18. In order that the sections may be connected as closely together as possible and to provide at the same time means for tightening the conveyer-belt of B', I employ plates 67 and 68, the former fastened to the end of one carrier-section and the latter slidable on the adjacent end of the other section and controlled by a screw 69 or equivalent device. 10 Each plate is provided with a half-box 70 71 to embrace the carrier-roller shaft and embraced and held together by a ring 72.

Under some circumstances should it be found impracticable to operate the shore conveyers from the barge, as where the haul is a very long one and the load unusually heavy, the shore conveyers may be run by an independent motor 73, Fig. 18, connecting through belts 74 and gears 75, with the carrier of B'. 15 Having thus described my invention, what I claim, and desire to secure by Letters Patent, is—

1. The combination in a cargo-conveyer of an elevator, horizontal, lateral feed-conveyers 25 by which burdens are delivered to the foot of the elevator, parallel guides between which the burden is carried said guides adjustable to and from each other to burdens of different sizes, horizontal discharge-conveyers, and 30 means for operating the several conveying means continuously and in unison.

2. The combination in a cargo-conveyer, of a vertically-disposed and vertically-adjustable elevator, having a burden-guide adjustable to 35 burdens of different sizes, means for supporting said elevator independently of the vessel being unloaded, a shore conveyer likewise supported independently of the vessel, lateral conveyers delivering burdens to the foot of 40 the elevator and means for driving the several conveying means in unison.

3. The combination in a cargo-conveyer, of an elevator supported independently of the vessel being unloaded and adjustable in relation to the vertical movements of the vessel 45 and to the level of the cargo in the hold, and means including a contractile deflector operating in conjunction with said elevator for automatically delivering burdens to the foot 50 of the elevator and for landing said burdens from the elevator.

4. The combination in a cargo-conveyer of an elevator, a saddle-support therefor, a transverse shore carrier, an endless traveling 55 burden-carrier upon the elevator, means for transferring burdens from the elevator-carrier to the transverse carrier, and an endless driving belt or rope and direction-pulleys whereby motion is transmitted to both the 60 horizontal and vertical carrier and the elevator, and vertical adjustment of the elevator permitted.

5. The combination in a cargo-conveyer of a transverse endless traveling belt or carrier, 65 an elevator-leg adjustably suspended and hav-

ing an endless chain of flights, means by which the carrying belts and flights are moved in unison, a transfer device consisting of a triangular frame, means for adjustably suspending it from the elevator-leg whereby packages are delivered from the elevator-flights to the transverse carrying-belt, and means for varying the shape of the transfer-block to suit the size of the packages. 70

6. In a cargo-conveyer, the combination 75 with vertical and horizontal coöperating burden-carriers, of a contractile deflector for automatically discharging the burdens from the first to the second conveyer.

7. In a cargo-conveyer, the combination 80 with two coöperating carriers disposed at right angles to each other, of a sectional jointed block by which the burdens are deflected from one carrier to and upon the other.

8. In a cargo-conveyer, the combination 85 with vertical and horizontal coöperating conveyers of a triangular deflecting-block disposable at the intersection of said carriers, said block having foldable sections supported at their ends upon foldable supports substantially as described. 90

9. The combination in a cargo-conveyer of a transverse endless-belt carrier, a boom and a mast or derrick from which the inner and the outer ends of said boom are adjustably supported, a vertically-disposed elevator with a saddle by which said elevator is adjustably suspended from the outer end of the boom and mechanism by which it may be raised or lowered and tilted with relation thereto. 100

10. In a cargo-conveyer, the combination of an elevator-leg, a transverse discharge-carrier, a boom, a saddle thereon in which the elevator-leg is movable, means for suspending it in said saddle, said means including drums or sprockets on the leg and chains connected with the saddle and said sprockets, and means for revolving the drums to raise or lower the elevator with relation to the transverse carrier. 105

11. In a cargo-conveyer, the combination of a horizontally-supported boom, an elevator consisting of a frame, a saddle and suspending-chains whereby it is adjustably supported from the outer end of the boom, sprockets 115 at top and bottom of the elevator-frame and endless traveling chains with transverse flights attached thereto and adapted to receive and raise packages, a floor extending from end to end of the elevator, and means for adjusting the floor to or from the conveyer-flights to support packages of different sizes. 120

12. In a cargo-conveyer, the combination of a vertical frame, a horizontal support, means for adjustably suspending the elevator from the outer end of the said support, an endless horizontal traveling conveyer, an endless chain of flights with sprockets at top and bottom of the elevator, over which they pass, a floor composed of bars or pipes extending 125 130

- lengthwise of the elevator and forming a support against which the packages upon the flights rest, means for adjusting said floor with relation to the flights, said means consisting of racks connected with the floor, pinions mounted upon longitudinally-journalized shafts, and worm-gears and means for actuating said gears whereby the floor may be moved to or from the flights.
13. In a cargo-conveyer, the combination of a horizontally-supported adjustable boom, an elevator adjustably suspended from the outer end thereof, an endless horizontally-movable belt and an endless chain of flights upon the elevator with means for transferring packages from the elevator to the transverse carrier, guide-bars upon each side of the movable carriers and means for adjusting said bars to or from the center, to suit different-sized packages, said means consisting of crank-arms with which the guide-bars are connected in parallel lines, and mechanism by which said crank-arms are moved in unison to advance or retract the connected guide-bars.
14. In a cargo-conveyer, an endless carrier including in combination, guide-bars, crank-arms by which said bars are supported upon opposite sides and parallel with the line of travel of the carrier, mechanism for moving the bars to or from each other, consisting of vertical shafts upon which the inner ends of the cranks are fixed, and a worm-gear by which the shafts are turnable in unison so as to advance the guide-bars equally from end to end.
15. In a cargo-conveyer, the combination of an endless traveling carrier, guides supported upon the outer ends of crank-arms upon opposite sides and parallel with the line of travel of the carrier, shafts upon which the inner ends of the crank-arms are fixed, worm-gears by which said shafts are revoluble, rope sheaves fixed upon the shafts and ropes passing around said sheaves connecting the sets of crank-shafts, whereby the movement of the worm-gear is transmitted to revolve all the shafts in unison and advance or retract the guide-bars parallel with the line of travel of the carrier.
16. In a cargo-conveyer, the combination of a transverse frame, an endless traveling belt or carrier movable thereon, an elevator-leg, means for suspending said leg and adjusting it up and down, an endless chain of flights or carriers, sprocket-wheels at top and bottom of the elevator-leg over which said carriers are adapted to travel, mechanism by which the elevator-carriers are driven in unison with the transverse carriers, said mechanism consisting of guide pulleys or idlers and a boom or support therefor, pulleys connected with the driving-sprockets of the elevator-carrier, ropes passing over said pulleys and the idlers, other pulleys located at the inner end of the boom over which the ropes pass, and tension and driving pulleys whereby the endless driving-ropes are caused to transmit power to the carriers, and the elevator-leg is permitted vertical adjustment without disarranging the driving mechanism.
17. In a cargo-conveyer, the combination of a transverse endless carrier, a vertically-movable endless carrier, and a boom or frame from which the vertical carrier is adjustably suspended, endless driving-ropes, pulleys about which said ropes pass at top and bottom of the elevator-leg, direction-pulleys over which the ropes pass and extend along the boom, other direction-pulleys over which the ropes pass to the driving and tension pulleys respectively, and swiveled yokes in which the direction-pulleys are journalized and by which they are maintained in the plane of travel of the connecting ropes or belts.
18. In a conveying apparatus, a horizontal endless conveyer, a frame therefor, and parallel lateral guides between which the burden is carried, said guides being adjustable to and from each other to burdens of different sizes.
19. In a cargo-conveyer, the combination of a transverse frame, an endless traveling belt movable thereon, a derrick or support, a boom and a swiveling cross-head upon which the inner end of the boom is supported, mechanism by which said inner end may be raised or depressed with relation to the derrick, an elevator-leg suspended from the outer end of said boom, an endless traveling carrier movable upon the elevator-leg, means for raising, lowering and swinging the elevator-leg with reference to the carrier, and a device adjustable upon the elevator-leg whereby packages are automatically transferred from the elevator-carrier to the transverse carrier.
20. In a cargo-conveyer, the combination of a transversely-movable endless belt and support therefor, an elevator-leg with endless traveling carriers, a saddle, chains and pulleys by which said leg is suspended, and a support therefor, a floor adjustable with relation to the flights over which floor the packages travel while being raised, a transfer device consisting of a triangular block, means for adjusting it up and down, said block being composed of jointed, foldable sections whereby its height is varied to suit the distance between the movable floor and the carrying-flights.
21. In a cargo-conveyer, the combination of a transverse endless carrier, an elevator adjustably suspended and a support therefor, an endless chain of flights and a longitudinally-disposed floor adjustable with relation to said flights to form a support for packages which are being elevated by the flights, and guides supported with relation to the flights and floor, and serving to prevent the packages from displacement while being elevated.
22. In a cargo-conveyer, the combination of a transverse carrier, an elevator-leg and a boom or support from the outer end of which

the leg is suspended and vertically adjustable with relation thereto, an endless chain of flights or carriers with sprockets at the upper and lower ends of the leg over which they 5 pass, a floor extending from end to end within the chain of flights and adjustable to or from the flights to form a support in conjunction therewith for the packages, guides exterior to the flights and parallel with the line of travel 10 of the packages to prevent their displacement, said guides being formed of extension or telescopic sections, the upper one of which is connected with the transverse carrier-frame, so that the guides are extended or contracted in 15 unison with the vertical movements of the elevator-leg.

23. The combination in a cargo-conveyer of an elevator-leg and a transverse carrier-frame, a boom to the outer end of which the leg is 20 adjustably suspended, an endless carrier having flights, sprockets at top and bottom of the elevator-leg over which they pass, a longitudinal floor located within the oppositely-moving sides of the carrier and adjustable with 25 relation to the flights to form a support for packages which are being lifted, said floor-strips being bent around the shaft of the lower sprocket, racks connected with the floor-strips at intervals, pinions mounted upon longitudinal 30 shafts engaging said racks, adapted to raise or depress the floor when turned, sleeves at the lower end through which the pinion-shafts are slid able, other sleeves fixed transversely to the first-named sleeves and suspended 35 upon the shaft of the lower sprocket-wheels.

24. In a cargo-conveyer, the combination of a transverse endless traveling belt, a boom or support, an elevator-leg adjustably suspended 40 from the outer end of the boom, an endless driving-belt and direction-pulleys whereby power is transmitted from said belt to drive the transverse and elevator carrier, clutches intermediate between the driving-pulleys and 45 the carrier, propelling-drums and sprockets and levers and operating-rods by which the clutches are thrown into or out of engagement whereby the carriers may be stopped or started.

50 25. The combination in a cargo-conveyer of a horizontal support, a saddle carried at the end of said support, an elevator-leg with burden-carrying means supported in said saddle, a transverse conveyer-frame having an end 55 supported in said saddle in relation to the elevator-leg and its conveying means, and an endless conveyer supported upon said frame, said conveyer extensible and contractible in length whereby the elevator-leg end of said conveyer

may be advanced toward or removed from the 60 elevator-leg conveying means, independently of the transverse supporting-frame.

26. The combination in a cargo-conveyer of a swiveled and vertically-adjustable horizontal support, a vertically-adjustable elevator 65 supported at the end of said support, a horizontal shore conveyer, endless driving means for operating the elevator and shore conveyers and swivel-supported direction-pulleys around which said endless driving means pass whereby the apparatus is adapted to any oscillatory 70 movement of the elevator.

27. The combination in a cargo-conveyer of a vertically-supported and adjustable elevator-leg, endless burden-carrying means thereon, 75 lateral conveyers delivering burdens to the foot of said leg and operable in unison with the conveying means on the elevator, supplementary conveyers delivering to said lateral conveyers and means at intervals along the 80 length of said lateral conveyers engaging operative means on said supplemental conveyers whereby the latter may be operated in unison with the lateral and elevator conveyers.

28. The combination in a cargo-conveyer of 85 a vertically-supported adjustable elevator-leg, sprockets at either end thereof, burden-carrying means passing around said sprockets, lateral conveyers delivering to the foot of said elevator-leg, supplemental conveyers delivering 90 to said lateral conveyers, means for driving the supplemental and lateral conveyers connecting with the lower sprocket on the elevator-leg, the means by which the supplemental conveyers are driven including a line-shaft parallel with the lateral conveyers and 95 having gear-teeth thereon at intervals adapted to engage corresponding gears of supplemental conveyers and a track in parallel with said shaft on which the driving end of 100 the supplemental conveyers are movably supported.

29. The combination with two aligned endless conveyers of means for connecting the adjoining ends of said conveyers and providing a 105 take-up for one of the belts thereof, said means comprising plates as 67 68 carried by said ends and having segmental boxes to embrace a carrier-roller shaft, means for retaining said boxes in position and means in conjunction with one 110 of said sets of plates for adjusting the tension of the belt substantially as described.

In witness whereof I have hereunto set my hand.

CHARLES H. ANDERSON.
